(57) **CLAIM**

The ornamental design for a dispensing device, as shown and described.

DESCRIPTION

FIG. 1 is an isometric view of a front, top, and left side of an ornamental design for a first embodiment of a dispensing device;

FIG. 2 is a front elevational view of the dispensing device; FIG. 3 is a rear elevational view of the dispensing device; FIG. 4 is a left side elevational view of the dispensing device, wherein the right side elevational view is a mirror image of the left side elevational view;

FIG. 5 is a top plan view of the dispensing device;

FIG. 6 is a bottom plan view of the dispensing device;

FIG. 7 is an isometric view of a front, top, and left side of an ornamental design for a second embodiment of a dispensing device;

FIG. 8 is a front elevational view of the dispensing device;

FIG. 9 is a rear elevational view of the dispensing device;

FIG. 10 is a left side elevational view of the dispensing device, wherein the right side elevational view is a mirror image of the left side elevational view;

FIG. 11 is a top plan view of the dispensing device; and,

FIG. 12 is a bottom plan view of the dispensing device.

The broken lines are for the purpose of illustrating environmental structure and form no part of the claimed design.
